Primary Examiner — Paula Greene(74) *Attorney, Agent, or Firm* — Senniger Powers LLP**CLAIM**

The ornamental design for an in ear earset, as shown and described.

DESCRIPTION

FIG. 1 is a perspective of an in ear earset of the present invention;

FIG. 2 is a front elevation of the earset;

FIG. 3 is a right elevation of the earset;

FIG. 4 is a top plan of the earset;

FIG. 5 is a rear elevation of the earset;

FIG. 6 is a left elevation of the earset; and,

FIG. 7 is a bottom plan of the earset.

Broken lines illustrate features forming no part of the claimed design.
